[57] **CLAIM**

The ornamental design for a decorative seasonal outdoor
light, as shown and described.

DESCRIPTION

FIG. 1 is an exploded perspective view of the decorative
seasonal outdoor light showing my new design;

FIG. 2 is a front elevational view thereof;

FIG. 3 is a rear elevational view thereof;

FIG. 4 is a right side elevational view thereof, the left side
elevational view being a mirror image of the view shown in
this Figure;

FIG. 5 is a top plan view thereof; and,

FIG. 6 is a bottom plan view thereof.
